(57) **CLAIM**

The ornamental design for the manipulable cubes base station, as shown and described.

DESCRIPTION

The present application relates to U.S. patent application Ser. No. 29/376,968 filed 14 Oct. 2010, now U.S. Pat. No. D 635,190 entitled Interactive Play and Learning System, which is hereby incorporated by reference in its entirety for all purposes as if fully set forth herein.

FIG. 1 is a top front perspective view of the manipulable cubes base station;

FIG. 2 is a top rear perspective view of the manipulable cubes base station;

FIG. 3 is a front view of the manipulable cubes base station;

FIG. 4 is a rear view of the manipulable cubes base station;

FIG. 5 is a view of one side of the manipulable cubes base station;

FIG. 6 is view of the opposite side of the manipulable cubes base station;

FIG. 7 is a top view of the manipulable cubes base station;

FIG. 8 is a bottom view of the manipulable cubes base station; and,

FIG. 9 is a front elevated perspective view of the manipulable cubes base station and its environment including a plurality of manipulable cubes.

The broken lines seen in FIGS. 2 and 4 are included for the purpose of illustrating the boundaries of the claimed design. The broken lines and surfaces within them form no part of the claimed design.

The broken lines seen in FIG. 8 are included for the purpose of illustrating portions of the manipulable cubes base station that form no part of the claimed design.

The portions of the drawings shown in broken lines in FIG. 9 illustrate the surrounding structure and environment which form no part of the claimed design.

1 Claim, 7 Drawing Sheets
